SWING

William H. Fry, Kansas City, Mo.

Application January 4, 1936, Serial No. 57,543

3 Claims. (Cl. 155—65)

This invention relates to swings and particularly to that type of swing having a seat carried by means of flexible suspending members and also having operating means.

5 The principal object of the instant invention is the provision of a suspended swing having a propulsion or operating means that permits of free pivotal movement of all the working parts when the swing is in motion.

10 A further object of this invention is the provision of a seat member suspended by a pair of front and a pair of rear flexible suspending members, a pivotally suspended foot rest carried by bars pivoted intermediate their ends to the seat member, and a pivotally mounted link interconnecting each of said arms to its adjacent suspending member, whereby the suspending members will be flexed as the foot rest is moved relative to the seat member.

15 Other objects are sturdiness of construction, ease of operation and adjustability to accommodate persons of different statures.

Reference will now be had to the drawing, wherein:

20 Figure 1 is a perspective view of a swing embodying this invention.

Fig. 2 is an enlarged, end elevation of the swing, with parts broken away for clearness.

25 Fig. 3 is an enlarged, sectional view, taken on line III—III of Fig. 2.

Fig. 4 is an enlarged, fragmentary view of a portion of the frame and arm, with the flexible supporting member attachment shown in elevation.

30 Fig. 5 is a vertical, sectional view, taken on line V—V of Fig. 2, and,

Fig. 6 is a fragmentary, sectional view of the front portion of one of the arms showing the pivotal connection of the foot rest carrying bar.

35 Throughout the several views, like reference characters will designate similar parts and the numeral 10 indicates a seat member comprising base members 12, arms 14, vertically disposed back members 16 and front posts 18. Back members and front posts are positioned and interlocked with base members 12 and arms 14 so as to form a rigid structure when the seat bottoms 20 and back boards 22 are secured in position. The front posts are held in operative position 40 with base members 12 by means of cleats 24 and angle iron 26 which has its vertical leg facing against post 18 and its horizontal leg extending rearwardly on the bottom of base member 12 where it is attached by means of screws 28 and 45 the tie rod 30.

This tie rod has an eye 72 at its upper end and extends downwardly through arm 14, thence through base member 12 and angle iron 26 where it is secured by means of a nut 32 which engages the threaded end 34 of the tie rod. For the purpose of quick assemblage, a dowel pin 36 is provided for positioning the front post 18 to the base member 12. Front posts 18 are secured to the arms 14 by screws or other suitable fastening means 38.

5 This swing seat is suspended by any suitable flexible members so as to permit free movement of the swing in any direction. These flexible suspension members are shown as chains 40 which are positioned at the proximal corners of 15 the swing. The rear pair of chains 40 are interconnected with links 42 which in turn are pivoted on bolt 44 extending through arm 14 and back member 16. This bolt serves also to tie together the parts of the swing frame.

20 The front pair of flexible suspension members is attached to the seat member through the intermediacy of links 46 and the tie rod 30, as clearly shown in Figs. 2 and 5. Arms 14 are projected forwardly of the seat proper and are each 25 provided with a slot 48, into which is fitted a vertically disposed bar 50. A pin 52 extends transversely through the arm and the bar 50, thereby pivoting the same intermediate its ends. Bar 50 is tubular in form and is provided at its 30 lower end with a telescoping rod 54 which is secured thereto by means of a bolt 56. A series of holes 58 formed through the lower end of 50 35 permits of vertical adjustment of rod 54. Carried by rods 54 and secured thereto by nuts 60 is a foot 30 board 62. This foot board extends entirely across and in front of the swing seat so as to be accessible to the occupant, regardless of his position in the swing.

40 The upper portion of bars 50 extends above arms 14 and in substantially parallel position with chains 40. A connecting link 64 pivotally mounted in bar 50 at 65 as shown in Fig. 3, extends rearwardly in a substantially horizontal 45 position and is pivotally connected at its rear end with chain 40 through the intermediacy of perforated plate 66, washer 68 and nut 70.

45 It is very evident that with this type of structure no sliding movement other than the rotary movement of the pivotal parts is present when the swing is in action. It is apparent that a straight 50 perforated bar might be substituted for link 64 by simply using pins to connect it with bar 50 and chain 40, thereby obtaining the same gen- 55

eral effect in so far as the relative movements of the parts are concerned.

During the operation of propelling this swing by means of the parts provided herein, it is very evident that bolt 44 will move through an arc having its center at 72, while the point 65 will move through an arc whose center is at 52, thereby maintaining 64 in a position substantially parallel with arm 44 without any relative sliding movement of the parts.

The most important feature of this invention is the manner in which force is transmitted from bar 50 to the flexible suspension member 44, which permits of a very definite and easy movement of the flexible member either forwardly or rearwardly and without any undue wearing action of the parts. The upper end 74 of bar 50 may be utilized as a hand hold for operating the swing.

It is not desired to limit this invention to the construction shown and described since many modifications may be made within the scope of the appended claims without departing from the spirit thereof.

Having thus described the invention, what is claimed as new and desired to be secured by Letters Patent is:

1. In a swing having a seat member suspended by a pair of front and a pair of rear, flexible suspending members, a foot rest swingably carried by vertically disposed, adjustable bars pivoted intermediate their ends to said seat member; and a horizontally disposed link pivotally interconnecting each of said bars to the adjacent front suspending member intermediate its ends whereby the front suspending members will be flexed as the bars oscillate on their pivots.

2. In a swing, a seat member suspended by a

pair of front and a pair of rear flexible suspending members and having end arms extending forwardly of said seat member; a vertically disposed bar pivoted intermediate its ends in each of said arms; a foot rest extending across the front of 5 said seat member carried by said bars; a link pivoted adjacent the upper end of each of said bars and to the respective adjacent suspending member intermediate its ends whereby said suspending members are simultaneously flexed as the foot board is moved relative to the seat member; and means to vary the distance from the seat to the foot rest.

3. In a swing having a seat member, an arm at each end respectively of said seat member, extending forwardly beyond the front edge of said seat member, and flexible members suspending said seat, at the ends thereof adjacent the front and rear edges respectively, the combination of a foot rest below the seat along the front edge 20 thereof; a bar at each end respectively of said foot rest for carrying the same; and a link interconnecting the said bar and the proximal front flexible member respectively, said bars each having pivotal connection with the forwardly extending end of the adjacent arm intermediate the ends of the respective bar, said links each being pivotally joined to their respective bar intermediate the upper end thereof and its pivotal connection with the arm whereby to provide an upwardly 30 projecting portion to serve as a grip for the operator, said links being attached to the front flexible members at a point intermediate their ends to permit flexing thereof as the foot rest is swinging about the pivotal connections between 35 the bars and arms.
